Term of patent 3½ years

(Cl. D80—9)

Fig. 1.

Fig. 2.

To all whom it may concern:

Be it known that I, Richard Vandenberg, a citizen of the United States, residing at Milwaukee, in the county of Milwaukee and State of Wisconsin, have invented a new, original, and ornamental Design for a Display Device, of which the following is a specification, reference being had to the accompanying drawing, forming part thereof.

Figure 1 is a perspective view of a display device embodying my design.

Figure 2 is an end elevational view of the display device.

The back of the display device is similar to that shown in Figure 1.

I claim:

The ornamental design for a display device, substantially as shown.
